(57) **CLAIM**

The ornamental design for a speaker frame, as shown and described.

DESCRIPTION

FIG. 1 is a top perspective view of the speaker frame in accordance with a preferred embodiment of the new design; FIG. 2 is a bottom perspective view of the speaker frame shown in FIG. 1

FIG. 3 is a top view of the speaker frame shown in FIG. 1; FIG. 4 is a bottom view of the speaker frame shown in FIG. 1; and,

FIG. 5 is a side view of the speaker frame shown in FIG. 1. The speaker frame illustrated in the drawings is symmetric, wherein all side views of the speaker frame are identical to the view shown in FIG. 5.
